UNITED STATES PATENT OFFICE

JULIUS CARLSON, OF BROOKLYN, NEW YORK

ADJUSTABLE CAP

Application filed December 5, 1927. Serial No. 237,604.

This invention relates to adjustable caps and particularly to the adjusting buckle and side pockets which are so designed that the cap may be quickly and easily adjusted and presents a neat and finished appearance throughout, and the loose ends or raw edges of the various adjusting elements are entirely concealed.

It has been customary in caps of this type to provide a pair of straps attached to the rear portion of the cap and meeting at the front of the cap, the front ends of the straps being connected to a suitable fastening element such as a buckle for adjustment. With the aforesaid construction, however, at least one loose end of the straps is visible and uncontrolled at all times thereby detracting from the good appearance of the cap by hanging loosely from the buckle. It has further been customary not to seam the lower front portion of the cap to the lower rear portion at the center of the sides and to provide a tongue member in connection with the rear edge of the front section which tongue member projects rearwardly and enters a suitable pocket in the lining of the rear section. With this construction the tongue member advances rearwardly into the pocket as the size of the cap is decreased and is partly withdrawn from the pocket as the size of the cap is increased. Said construction, however, has the defect that the lining of the cap at the side pockets is likely to be puckered or bunched in pleats about the pocket as the size of the cap is decreased, that an unseen portion or raw edge of the lining may appear when the size of the cap is increased, and that the tongue may even be entirely withdrawn from the pocket if an attempt is made to enlarge the size too much.

My invention contemplates a construction wherein the disadvantages above pointed out are eliminated, and a cap presenting a finished appearance throughout at all times and for all sizes, is provided.

The various objects of my invention will appear from the description which follows and from the drawings, in which,

Fig. 1 is a perspective view of my improved cap, the tip being raised to expose the

adjusting straps, and the tongue on the front section being shown in dotted lines.

Fig. 2 is an inside side view of a portion of the cap at the sides or pockets, the lining and the pocket formed thereby having been removed to show more clearly the construction of the tongue member.

Fig. 3 is a similar view of the same with the lining in place.

Fig. 4 is a perspective view of the cap lining with its adjustable sides in their most extended position for the largest size, showing particularly the construction of the lining at the sides where the adjustment takes place.

Fig. 5 is a similar view of a portion of the same, showing the position assumed by the lining when the size of the cap has been somewhat decreased.

Fig. 6 is an inside view, similar to Fig. 3, showing the lining in the position it assumes when extended.

Fig. 7 is a horizontal section of part of the adjusting straps and of the means for holding the straps in adjusted position.

Fig. 8 is a similar view of a modified form of the strap holding means, and

Fig. 9 is a perspective view of the same.

In the practical embodiment of my invention, the cap is formed in the usual way and for convenience will be considered as divided into two sections comprising the front section 10 and the rear section 11. The sections are suitably joined together in the customary manner and are not seamed together at two points in the lowermost edges thereof, that is, at the openings 12 at the sides of the cap. To the rear section 11 and just rearwardly of the open edge 12, is secured one of the adjusting straps 13, which is brought around to the front of the cap to rest on the visor 14. The most forwardly end 15 of the strap 13 (Fig. 7) is secured to the cross bar 16 of the buckle 17 in any suitable manner. For instance, in Fig. 7, I have shown the end 15 passed about the cross bar 16 and secured in place thereto, as by means either of staples or seams 18, in a manner which is well known in the art and which need not therefore be described in detail.

If, however, it is desired to eliminate the

staples or seams 18, suitably projecting curved prongs 19 may be provided on one edge 20 of the cross bar 16, and said prongs may be passed through the end portion 15 of the strap 13 and into the body portion of said strap. The prongs 19 may then be readily turned over against the rear face of the cross bar (Fig. 8) to permanently secure the strap end 15 in place.

10 It will be understood that before the strap 13 is secured to the buckle 17, it is first passed through the loop 21. Said loop is secured to the most forwardly end 22 of the strap 23 which extends about the other side of the cap toward the front thereof. The strap 23 passes through the space 24 of the buckle 17 from the rear to the front thereof, then past the front face of the cross bar 16 and then through the space 25 of the buckle. The portion 26 of the strap 23, thereby arranged in the buckle between the outside ends 27 and 28 thereof, not only conceals the end 15 of the other strap 13 secured about the cross bar but also covers and conceals the cross bar itself.

15 20 25 30 35 40 45 50 55 60 65

Teeth or prongs as 29 may be provided on the inner ends of the edge 27 of the buckle for engaging and passing into the strap 23 when the straps are relatively tensioned so that movement of the buckle 17 relatively to the strap 13 is ordinarily prevented. If, however, it is desired to adjust the cap to a new size, the teeth 29 may be withdrawn by merely pulling the buckle 17 toward the left as viewed in Figs. 1 and 7, thereby moving the buckle relatively to the strap 23 and away from the end 22 thereof, whereupon the buckle 17 may be further adjusted in either direction to change the effective lengths of the straps 13 and 23 and thereby to change the head size of the cap.

The buckle 17 is preferably made of a single piece of sheet material and is preferably made concave forwardly so that the arrangement of the straps at the cross bar does not appear unduly bulky from the front of the cap.

50 The front section 10 of the cap is provided with a rear extension 30 in the form of a tongue having an inclined upper edge 31. The lower edge of the tongue is stiffened as by means of the stiffening member 32 of stiff canvas or other suitable material seamed thereto and continued if desired around to the visor 14. The lowermost edge 33 of the tongue and of the front section 10 is turned inwardly about the stiffening member and seamed thereto as by means of suitable stitching 34. (Fig. 2.) As has been explained hereinbefore, the front section 10 remains unattached to the rear section 11 along an edge 12 at the side of the cap, but the tongue 30 projects past that edge and the outside of the tongue being of the same material as the remainder of the section 10, thereby obstructs and closes any opening which might other-

wise appear between the front and rear sections of the cap and causes the cap to appear like any ordinary non-adjustable cap. In order to conceal the tongue 30 from view on the inside of the cap and at the same time to form a pocket for the reception of said tongue, I prefer to use the usual lining 35 constructed and arranged in a peculiar manner so as to present at all times a finished lower edge at the upright side edge 12 of the cap. The sides 36 of the lining 35 when formed in two or more parts are suitably seamed together near the edge 12 of the cap as by means of the seams 37. The lining is furthermore preformed in a fold 38, the fold being permanently maintained by means of the stitching 39 in the lower edge thereof so that the lining may be seamed in place in the cap in its folded condition. The rear edge 40 of the lining is secured to the lowermost edge 41 of the rear section 11 (Fig. 6) by means of suitable stitching 42 running up to the permanently folded edge 43 of the fold 38. The front edge 44 of the lining is similarly seamed to the lowermost edge 45 of the tongue 30 as by means of stitching 46 running up to a point adjacent to the fold line 43 and indicated by the notch 47 in Figs. 4, 5 and 6. It will therefore be seen that only that portion 48 of the lining behind the permanent fold 38 and between the points 47 and 37 is free and unseamed to the lower edge of the cap. The portion 48 being at all times covered by the fold 38 is always invisible whereby the lower edge of the cap presents a finished appearance, no raw or unseamed edges being exposed at any time to view.

In Figs. 4 and 6, I have shown the lining and the cap sections in relatively extended positions giving the largest head size. In this position, the tongue 30 cannot be pulled forwardly to withdraw it entirely from out of the pocket or space 49 between the lining and the inner face of the cap sections, since the seamed fold 38 prevents further extension of the lining from the positions indicated. The tongue may however be moved rearwardly, that is further into the space 49 being allowed so to move by reason of the independence of the cap sections 10 and 11 at the edge 12, and the fact that the portion 48 of the lining edge is also free. The point 47 of the lining may thereby move with the tongue to which it is secured from a point directly behind the fold line 43 to a point rearwardly of the seam 37 of the fold, a distance equal to the length of the unseamed edge portion 48 to decrease the head size therefore on each side of the cap by twice the length of the unseamed lining portion 48. Altogether, on both sides, the adjustment possible, is substantially equal to four times the length of the unseamed edge 48.

It will be seen that I have provided an adjustable cap wherein the ends of the adjust-

ing strap are at all times concealed, that the adjustment may be made quickly and accurately, and that the cap is finished throughout in such a manner that the guiding tongue is hidden at all times and cannot be withdrawn, and the lining presents a finished appearance at all times.

It will further be understood that I do not intend to limit myself to the specific structure shown and described, but that I intend the foregoing to be exemplary of my invention, and intend that the limits of the invention be determined only by the appended claims and the state of the prior art.

I claim:

1. In an adjustable cap having front and rear sections relatively movable at their lower edges, a lining having a permanently formed fold, stitching securing the fold to the lower edge of the rear section, stitching securing the front part of the lining to the front section leaving an unseamed lower edge on said lining behind the fold and substantially equal in extent to the width of the fold at its lower edge, a tongue on the front section passing between the fold and the rear section and projecting rearwardly of said fold, straps secured to the rear section at the sides thereof and passing about the front section to the front of the cap, and means for varying the effective lengths of said straps.

2. In an adjustable cap, relatively adjustable front and rear sections, means for adjusting said sections, a lining for said sections, a permanently formed fold in said lining at the sides of the cap, and stitching securing the rear lower edge of the lining and the folds thereof to the rear section and the front lower edge to the front section, said stitching being omitted from the lining along that part of the lower edge immediately behind said fold for allowing limited movement of the front part of the lining relatively to said fold, while the unstitched lining portion is concealed at all times to form a finished lower edge in the cap.

JULIUS CARLSON.
